UNITED STATES PATENT OFFICE.

HOWARD F. GORSUCH, OF GALION, OHIO, ASSIGNEE TO THE GALION IRON WORKS & MFG. CO., OF GALION, OHIO, A CORPORATION OF OHIO.

FEEDING MECHANISM FOR ELEVATORS.

Application filed July 29, 1925. Serial No. 46,693.

To all whom it may concern:

Be it known that I, HOWARD F. GORSUCH, a citizen of the United States, residing at Galion, in the county of Crawford and State of Ohio, have invented certain new and useful Improvements in Feeding Mechanisms for Elevators, of which the following is a specification.

This invention relates to means for feeding material to elevators, and particularly to certain improvements upon the construction illustrated in my prior Patent #1,440,594, granted January 2, 1923, on automatic feeders for elevators.

In order that this mechanism may be understood in its general features, it may be stated that in a certain type of standard screening or handling mechanism the material to be screened or handled is received in a pit disposed below a railroad track into which the lower end of an upwardly extending elevator frame extends, this elevator frame carrying an endless elevator provided with buckets, the material being lifted from the pit by the buckets, carried upward, and then discharged into a series of screening drums or otherwise treated.

It is desirable in mechanism of this kind to provide for an even feed of material to the buckets or elevator so as to prevent the buckets from becoming filled to overflowing at one time while at another time the buckets will be running with very little in them.

In my prior patent, I illustrated a mechanism of this character comprising a reciprocating conveyor or chute into which the material was discharged and which by its reciprocation caused the material to travel forward and be discharged into a spout and from thence to the elevator buckets, and I showed means whereby the chute could be reciprocated by power taken from the elevator driving mechanism.

The object of the present invention is to improve upon the chute or horizontal conveyor construction by providing improved means whereby this oscillating conveyor is supported for oscillation, and to provide improved means whereby this conveyor may be oscillated which will permit the conveyor

oscillating mechanism to be driven from the lower pulley of the upwardly extending conveyor and do away with the necessity of using other means for transmitting power thereto, this construction further permitting 55 of the sprocket chain being from time to time tightened to take up slack.

A further object is to provide a mechanism of this character wherein the conveyor oscillating mechanism may be readily disconnected from the driving mechanism for the upwardly extending conveyor or operatively connected thereto by means of a clutch.

A still further object is to provide improved means at the rear end of the reciprocating conveyor whereby as the conveyor moves rearward the material on the conveyor will be shifted forward or toward the discharge end of the conveyor, and to provide an improved detailed construction 70 for this purpose including a fixed plate against which the bulk of the material bears and an adjustable plate yieldingly held in engagement with the bottom of the reciprocating conveyor. 75

Other objects will appear in the course of the following description.

My invention is illustrated in the accompanying drawings, wherein:—

Figure 1 is a top plan view of an elevating and conveying structure constructed in accordance with my invention;

Figure 2 is a vertical longitudinal sectional view on the line 2—2 of Figure 1;

Figure 3 is a transverse sectional view on 85 the line 3—3 of Figure 2;

Figure 4 is a fragmentary longitudinal sectional view of the rear end of the trough.

Referring to these drawings, 10 designates a pit or equivalent structure having a 90 relatively narrow and relatively shallow extension 11 which extends beneath the railroad rails 12. A wooden platform 13 covered upon its upper face with steel plates and resting upon the ties 14 is disposed on 95 each side of the shallow portion 11 of the pit and extends partially thereover, leaving a longitudinally extending opening 15 across which the rails 12 extend.

Extending downward into the main por- 100

tion of the pit 10 is an elevator frame, designated generally 16 and which may be of any suitable construction, and this elevator frame carries at its lower ends the 5 sprocket wheels, rollers or equivalent elements 17 over which the endless belt or other like conveyor 18 passes. The lower wheels 17 or rollers are mounted upon a lower conveyor shaft 19, which in turn is driven by the 10 conveyor belt itself. The elevator or conveyor is driven from a head shaft mounted at the upper end of the frame. Any suitable means may be used for this purpose.

The side walls of the pit 11 are defined by 15 the railroad ties 20, and extending over the tops of these railroad ties are the metal plates 21. Each of these plates is downwardly flanged, as at 22, so that these plates form the guards for the reciprocating trough 23. This trough 23 has a width greater than the distance between the guards 22 and has upwardly extending sides 24 which extend upward on the outside faces of the guards 22 and then extend outward and downward 25 so as to form tracks 26, as they may be called, which rest upon rollers 27 mounted upon the upper series of railroad ties 20. Any number of these rollers may be used but the reciprocating trough 23 is entirely supported 30 upon these rollers and reciprocates beneath the guards 22, the forward end of the trough projecting out beyond the pit 11 and into proximity to the lower portion of the conveyor 18.

35 It is obvious now that the material discharged into the opening 15 will be discharged into the reciprocating trough and as this trough is reciprocated the material will be forced forward. The trough is reciprocated by means of an equalizer bar 28 which is pivotally connected to the bottom of the trough at the middle of the equalizer bar, the equalizer bar extending outward beyond the trough on each side and having 40 trunnions 29 formed at the ends of the equalizer bar. Connecting rods 30 have their heads 31 at the inner ends of the connecting rods engaged with said trunnions and the rods extend toward the main conveyor and 45 are connected to cranks 32 mounted upon a transverse shaft 33. This transverse shaft carries upon it the drive sprocket wheel 34 which is driven by a sprocket chain 35 which passes over a sprocket wheel 36 on the shaft 19. This sprocket wheel 36 is connected to the shaft 19 by means of a clutch 37, the 50 movable member of which is operated by means of the clutch operating handle 38. The shaft 19 is supported by end supporting 55 members 39 and these end supporting members in turn support a chute 40 which discharges onto the endless conveyor 18. The extremity of the reciprocating conveyor overhangs this chute and discharges thereinto.

The frame 16 of the main conveyor is held in fixed relation to the walls 20 by means of bars 41. Mounted upon one of these bars 41 is an idler sprocket wheel 42 which engages with the sprocket chain 35 and acts as a belt 70 tightener therefor. This idler sprocket wheel is mounted upon a lever 43 pivoted at 44 upon the bar 41 and the opposite end of this lever from the idler sprocket wheel being arcuate and provided with a series of 75 openings 45 through which a pin or screw may be passed engaging the brace 41 so as to thereby hold the sprocket chain tightener in adjusted position.

Extending across the space between the 80 rear ends of the ties 20 is a supporting plate 46 which bears against one of the rails 12, and disposed immediately in advance of the supporting plate are the downwardly and forwardly extending guides 47 which carry 85 the stationary end plate 48 which extends downward from a point immediately beneath one of the rails 12 to a point almost touching but spaced from the bottom of the conveyor trough 23. Immediately behind this stationary plate 48 there is an adjustable plate 49 which extends down into close contiguity to the upper face of the bottom of the conveyor trough 23 and yieldingly bears thereagainst. To this end the plate carries an 90 angle iron 50, and mounted beneath the plate 49 are a plurality of supporting fingers 51, the forward ends of which extend loosely into perforations in the angle iron 50. The rear ends are engaged by vertical bolts 52 100 passing loosely through the rear ends of the fingers and carrying the springs 53 bearing upward on the rear ends of the fingers. These fingers fulcrum upon a transverse angle iron 54. Thus the plate 49 is urged 105 downward yieldingly against the bottom of the trough and the springs 53 act to take up wear.

With this construction, the rear or adjustable end plate is urged downward against 110 the bottom of the reciprocating trough by means of the spring 53 and the tension of these springs may be adjusted by tensioning the nuts on the lower end of the bolt 52. A steel plate 54^a is provided to close the rear 115 end of the pit 11 rearward of the outer rail 12 so as to prevent anyone accidentally falling into this pit.

The operation of this mechanism will be 120 obvious. Assuming that the main elevator or conveyor is operating, the clutch element 37 is thrown into engagement with the corresponding clutch element on the shaft 19 and this drives the shaft 33 and the crank 32 which, through the connecting rods and the 125 equalizer bar 28, cause the reciprocation of the conveyor trough 23. As the conveyor trough moves rearward, the material will be caused to feed forward by striking against the plates 48 and 49 and as the conveyor 130

trough moves forward the impetus will carry a certain amount of material forward into the hopper 40 and thus into the buckets of the main conveyor. The reciprocation of the trough gives an even feed of material, acts to level the material within the reciprocating conveyor, and causes the material to feed equally and evenly to the buckets so that no one of the buckets is overloaded. 10 The equalizer bar 28 is pivotally connected at its middle to the trough bottom 23 so that when the erector sets this plant up the screening plant, including the elevator and the feeder, do not have to come on an exact 15 line in order to get the connecting rods to fit and there will be no more stress on one side than on the other when the device is working.

By driving the crank shaft 33 from the 20 lower shaft 19 of the main elevator instead of operating the driving mechanism from a special driving pulley, as shown in Figure 1 of my prior patent, I very much simplify the mechanism and provide for a ready connection and disconnection of the driving 25 mechanism for the reciprocating conveyor. Furthermore, I can easily apply a sprocket chain tightener to the mechanism. The means for supporting the reciprocating 30 trough is a considerable improvement over the mechanism illustrated in my prior patent, inasmuch as the trough is now hung upon rollers, as it were, and these rollers are disposed above the trough and practically 35 housed from dirt, dust or other material which is likely to interfere with the free operation of the trough on the rollers. Furthermore, this mechanism is much more simple than that illustrated in my prior patent.

40 I claim:—

1. A feeding mechanism of the character described including a conveyor formed to provide parallel, downwardly extending side walls held from movement, a reciprocatable trough-shaped bottom having side walls extending up exteriorly of the fixed side walls and at their upper margins outwardly flanged, rollers fixedly supported exteriorly of the side walls of the trough-shaped bottom and upon which the flanges rest, and means for reciprocating the bottom.

3. A feeding mechanism of the character described including parallel, downwardly extending side walls held from movement, a reciprocatable trough-shaped conveyor extending across the lower edges of the side walls and extending up exteriorly to the side walls, the upper margins of said trough-shaped conveyor being outwardly flanged and then downwardly flanged, supporting members mounted on each side of the conveyor, and rollers mounted upon the supporting members and upon which the outwardly extending flanges of the trough-shaped conveyor rest.

3. A feeding mechanism of the character described including a reciprocatable trough-shaped conveyor, an end plate extending downward and forward into the conveyor at an angle thereto, and means for resiliently urging said end plate downward and forward into approximate contact with the bottom of the conveyor. 70

4. A feeding mechanism of the character described including fixed, depending, side 75 walls, a trough-shaped conveyor mounted below the side walls and including a bottom plate having upwardly extending sides exteriorly of the fixed side walls, means for supporting said trough-shaped conveyor for reciprocating movement, downwardly and forwardly extending guides at the rear ends of said trough-shaped conveyor, forward and rear end plates disposed in said guides, the forward end plate being stationary and having 80 its lower edge spaced from the bottom of the trough-shaped conveyor, the rear end plate being adjustable and having its lower edge in approximate contact with the bottom of the trough-shaped conveyor. 85

5. A feeding mechanism of the character described including a reciprocatable trough-shaped conveyor, a stationary end plate extending down into the conveyor and having 90 its lower edge spaced from the bottom thereof, an end plate disposed rearward of the first named end plate, and means yieldingly supporting the second named end plate with its lower edge in approximate contact with the bottom of the conveyor. 95

6. A feeding mechanism of the character described including a reciprocatable trough-shaped conveyor, a stationary end plate extending down into the conveyor and having 100 its lower edge spaced from the bottom thereof, an end plate disposed rearward of the first named end plate, means yieldingly supporting the second named end plate with its lower edge in approximate contact with the bottom of the conveyor including downwardly depending bolts, compression springs 105 mounted upon the lower ends of the bolts, supporting members having their rear ends mounted upon the bolts and resting upon the compression springs, the forward ends of the 110 supporting members having openings, and pins extending from the second named plate and extending into said opening.

7. A feeding mechanism of the character described including a reciprocatable trough-shaped conveyor, a stationary end plate extending downward into the conveyor and having its lower edge spaced from the bottom thereof and an end plate extending parallel to the first named end plate but 120 held from movement with the trough, and means yieldingly urging this second named end plate down against the bottom of the trough. 125

8. A feeding mechanism of the character 130

described including a reciprocatable trough-shaped conveyor, an end plate extending downward and forward into the conveyor at an inclination thereto, and a supplementary end plate disposed parallel to and behind the first named end plate, and means supporting this supplementary end plate against

movement with the conveyor but yieldingly urging the supplementary end plate downward and forward against the bottom of 10 the trough.

In testimony whereof I affix my signature.

HOWARD F. GORSUCH.
